UNITED STATES PATENT OFFICE.

ARTHUR BEDWARD SPENCER AND FRANK EDWARD WALKER, OF HUCKNALL TOR-KARD, ENGLAND, ASSIGNORS TO GEORGE SPENCER, OF LUTTERWORTH, LEICESTER-SHIRE, ENGLAND.

DRIVING AND SUPPORTING MEANS FOR SEWING MACHINES AND THE LIKE.

Application filed January 17, 1925, Serial No. 3,114, and in Great Britain February 4, 1924.

This invention relates to driving and supporting means for sewing machines and the like, and is applicable especially where a number of machines are arranged in series 5 along opposite sides of a bench, stand or table and driven from a running shaft thereunder, the drive to the individual machines being transmitted from the shaft by means which are under the control of the 10 operator by a treadle or other suitable member.

In arrangements of the kind concerned two systems of drive have heretofore been employed. In one of said systems the machines in the opposite rows were driven 15 from a single driving shaft carried by cross members on the bench standards. This shaft was a slow running shaft and the drive to the individual machines was obtained through 20 the medium of a transmitter carried under the bench, that is to say there was a transmitter for each machine, each transmitter was driven by belt from the running shaft, and drove the machine by a second belt. 25 This system was open to the objections that the slow speed belt drive from the shaft to the transmitters was not efficient, the belts between the transmitter and the machines were too short to give good services, the 30 drive from the running shaft to the machines was not direct, and the transmitters occupied an undesirable amount of space under the bench in the region of the operator's knees.

In the other system of drive previously 35 employed a separate driving shaft has been provided for each row of machines each shaft being driven separately, usually by an electric motor. In such cases the driving shafts were driven at high speed and were 40 provided thereon with transmitters from which the drive to the machines was taken by belt there being a separate transmitter for each machine. The running shafts were located comparatively close up under the 45 bench and the transmitters thereon were controlled by the operators of the individual machines. The disadvantages of this system are, the running shafts and their associated parts are not conveniently accessible for in-

spection, lubrication, adjustment, repair and 50 like purposes; the shafts and guards which cover the transmitters thereon occupy an undesirable amount of space under the bench near the operator's knees; the belt drive from the transmitters to the machines is short; 55 and the duplicate shafts and their bearings and motors make the equipment expensive both as regards initial cost and cost of running and upkeep.

The aim of the invention is to provide a 60 form of drive which will combine the advantages of the two systems referred to without the disadvantages thereof.

The form of bench usually adopted for 65 sewing machine arrangements of the type concerned consists of a table of suitable length according to the number of machines in the rows, said table being supported by side standards fixed to the floor. For each machine there is generally provided a vertical seat post extending from the table to 70 the floor and carrying a seat for use by the operator when using the machine.

In connection with sewing or like machine 75 arrangements of the double row type already referred to, the present invention constitutes an improvement for the purposes of simplifying the arrangements; reducing the initial, running and upkeep costs of same; providing more clear space for the operator's knees 80 under the bench; providing a longer belt drive for the individual machines; rendering the running shaft and its associated parts more accessible and capable of being 85 examined by observation without removal of the guards; obtaining balanced end thrust on the driving shaft; and simplifying the bench structure.

According to the invention the machines 90 in both rows are driven from a single high speed shaft. That is to say, instead of using two running shafts one for each row of machines, or a single slow speed shaft and intermediate transmitters a single high speed shaft is provided from which the drive 95 to the machines in both rows on the bench is taken direct from transmitters thereon. This feature eliminates a driving shaft, its

motor and bearings and provides a direct drive from the shaft to the machines.

The single driving shaft is suitably located so that the drive to the machines in the opposite rows can be taken in a convenient manner and so as to enable a comparatively long driving belt to be used for such machine. For instance, by arranging the single driving shaft at a low level and in such position that the driving belts between said shaft and the machines in the two opposite rows on the bench are disposed angularly like a V, not only can a long belt drive be obtained but the running shaft is positioned where it is readily accessible. This arrangement provides a clear space underneath the bench along each side above the operator's knees which space has heretofore been occupied either by the transmitters or by the two driving shafts.

In order to enable the single high speed driving shaft to be rigidly mounted in a suitable position for transmitting the drive direct to the machines, the invention includes as one of its features an improved bench structure in which the table is supported by central upright standards instead of side standards as heretofore. The central upright standards provide a means for carrying the driving shaft in a rigid manner at a convenient level between the bench and the floor which arrangement is considered better than the previous one wherein the driving shafts were supported at a higher level near the underside of the bench by the bench leg or a cross web thereon. Moreover the central standard arrangement, by eliminating the side standards, provides more clear space under the bench along each side which is an obvious advantage seeing that the operator's are not so cramped as heretofore and there is less obstruction when it is desirable or necessary to have access to the running shaft or its associated parts.

In further describing the invention reference will be hereinafter made to the accompanying drawing wherein:-

Figure 1 is a front elevation of a complete section of the improved driving arrangement and bench structure.

Figure 2 is a sectional side elevation of the same.

Figure 3 is an elevation, partly in section, of one end of a transmitter, and

Figure 4 is a section taken on line II-II of Figure 3.

Figures 1 and 2 are drawn to a smaller scale than Figures 3 and 4.

According to a convenient embodiment of the invention the bench 1 is supported at various points throughout its length by a central upright standard 2 which preferably consists of a casting adapted for fastening to the floor such as by screws or bolts and carrying at the top a horizontal beam

casting 3 bolted to the standard, said beam being provided with a vertical slot 4 for passage of a securing bolt 5 (or bolts) so that the beam can be adjusted in height on the standard 2. Attached to the beam at opposite ends thereof are vertical tie rods 6 the lower ends of which are secured to the floor in any suitable manner. If desired said tie rods may also be utilized as seat posts. The standard 2 has attached thereto a bearing member 7 for the driving shaft 8. This bearing member is preferably attached by means of a bracket 9 which is capable of adjustment on the standard to enable the shaft 8 to be properly aligned.

For actuating the individual machines from the running shaft 8 the latter is provided with drive transmitting means preferably of a kind similar to that described in the specification of British Patent No. 139693 corresponding to U. S. Patent No. 1,382,133. These transmitters include a bearing member for supporting the shaft and in the present improved arrangement we make the transmitters double, that is to say instead of a single transmitter we combine two transmitters with the same bearing member one transmitter being used to drive a machine in one row and the other being used to drive a machine in the other row. In the drawings, 10 represents a machine in each row. Conveniently the bearing member 7 is situated between the two transmitters which are disposed in opposite directions to each other, the drive from one being transmitted by an open belt 11 and that from the other by a crossed belt 12. This form of drive balances the end thrust on the driving shaft. According to a practical embodiment of the double transmitter, one end of which is shown partly in section in Figure 3, the belt pulleys 13 are freely mounted by means of a ball or other anti-friction bearings (not shown) of any suitable type on sleeves 14 slideable in the bearing member 7 on opposite sides of a ball or other bearing (not shown) therein which carries the shaft 8. The bearing member 7 is provided with flanges 15 fitted with leather or other rings 16 adapted to engage the adjacent faces of the pulleys thereby forming brakes. The pulleys are also fitted with friction rings 17 or the like and for driving purposes the pulleys are moved in opposite directions to each other so as to press the friction rings against the opposing surfaces of driving clutch member 18 keyed on the running shaft. Thus the end thrust on the shaft is balanced.

Instead of moving the sliding sleeve 14 of each transmitter by means of a lever as described in the aforesaid specification, we prefer to obtain this movement by means of a pin 19 or equivalent which projects radially from the sleeve through an inclined or cam

slot 20 in the bearing member 7 and is connected to a treadle 21 by suitable intermediate connections, such for example, as a rod or link 22 a bar or link 23 fulcrumed upon a bracket 24 fastened to the floor, and a connecting link 25 one end of which is attached to the bar or link 23 and the other to a rod 26 which projects laterally from the treadle. There is also attached to the pin or member 19 one end of a tension spring 27 the opposite end of which is anchored to a pin 28 secured in the bearing member 7 whereby the pulley 13 is normally held in contact with the brake ring 16. Upon depression of the treadle the pin or member 19 turns the sleeve 14 in the bearing member 7 and owing to the angularity of the slot imports also an end-wise movement to the sleeve thereby moving the pulley out of engagement with the ring 14 and pressing it against the opposing face of the driving member 18. Instead of controlling the pin of each sleeve by a separate spring the two pins may be controlled by the same spring, for instance, they may be connected by a tension spring. The treadles 21 are each preferably fulcrumed upon uprights or brackets 29 attached to the floor in a rigid manner. This enables the treadle to be conveniently positioned to suit the operator.

In order to efficiently guard the running shaft and its associated parts and at the same time enable the same to be readily examined by observation during running we provide along opposite sides of the same a guard 30 of woven wire, wire netting or similar openwork material. These guards are arranged in the form of a V, as shown in Figure 2, so as to enclose the running shaft and parts thereon and the belt drives from the transmitters to the machines. The guards may consist of suitable frames formed by rods or bars carrying the woven wire or equivalent material. Conveniently said frames are held in position by attachment in a removable manner at the top and bottom to longitudinal bars or rods 31 supported by the horizontal beams 3 and the central standards 2 respectively of the bench structure. To this end the perpendicular members of the guards may be bent at their ends to form hooks which engage over the bars or rods 31. Or recessed lugs or other suitable devices cast on or attached to the horizontal beams and central standards may be provided instead of the bars or rods 31 for the attachment of the guards. The guards, being of openwork character, enable the enclosed parts to be seen therethrough and thus enable frequent examination to be made without removal of the guards.

The shaft 8 may be driven either directly or through suitable control gear from any convenient source of power, such, for example, as an electric motor which may occupy

any position with relation to the bench as may be found suitable or desirable.

The details of construction may be varied without departing from the scope of the invention.

What we claim then is:

1. Driving means for a double row of sewing or like machines arranged on a bench supported by central upright standards, comprising bearings on said standards, a single high-speed shaft carried by the bearings, transmitters associated with the bearings and arranged in two sets, those of one set opposing those of the other set, means for controlling the transmitters, open belts for transmitting the drive from the transmitters of one set to the machines in one row, and crossed belts for transmitting the drive from the transmitters of the other set to the machines in the other row.

2. Driving means for a double row of sewing or like machines arranged on a bench supported by central upright standards, comprising bearings on said standards, a single high-speed shaft carried by the bearings, sleeves slideable in said bearings, pulleys freely mounted on the sleeves, brake discs combined with the bearings for arresting rotation of the pulleys, means for normally holding the pulleys against the brake discs, driving clutch members on the shaft, treadles and intermediate connections for moving the pulleys into engagement with said clutch members, and belts for transmitting the drive direct from the pulleys to the machines.

3. Driving means for a double row of sewing or like machines arranged on a bench supported by central upright standards, comprising bearings on said standards, a single high-speed shaft carried by the bearings, sleeves slideable in said bearings and arranged in two sets, those of one set sliding in an opposite direction to those of the other set, pulleys freely mounted on the sleeves, brake discs combined with the bearings for arresting rotation of the pulleys, means for normally holding the pulleys against the brake discs, driving clutch members on the shaft, treadles and intermediate connections for moving the pulleys into engagement with said clutch members, open belts for transmitting the drive direct from the pulleys of one set of sleeves to the machines in one row, and crossed belts for transmitting the drive direct from the other pulleys to the machines in the other row.

4. Driving means for a double row of sewing or like machines arranged on a bench supported by central upright standards, comprising bearings on said standards, a single high-speed shaft carried by the bearings, sleeves slideable in said bearings, pulleys freely mounted on said sleeves, brake discs combined with the bearings, driving clutch members on the shaft, pins fixed in the

sleeves and projecting therefrom through inclined slots in the bearings, springs controlling the movement of said pins in one direction, treadles and intermediate connections for moving said pins in the other direction, the movement of said sleeves bringing the pulleys into alternate engagement with the

clutch member and brake disc, and belts for transmitting the drive direct from said pulleys to the machines.

In testimony whereof we have signed our names to this specification.

ARTHUR BEDWARD SPENCER.
FRANK EDWARD WALKER.
